[57]

CLAIM

The ornamental design for a sculpture, as shown.

DESCRIPTION

FIG. 1 An isometric view of a sculpture showing my new design;

FIG. 2 A top plan view thereof; the bottom plan view being a mirror image thereof;

FIG. 3 A front elevation thereof; the rear elevation being a mirror image thereof; and,

FIG. 4 A side elevation thereof; the opposite side elevation being a mirror image thereof.

*Fig. 1**Fig. 2**Fig.3*
